UNITED STATES PATENT OFFICE.

JESSE A. B. SMITH, OF STAMFORD, CONNECTICUT, ASSIGNEE TO UNDERWOOD TYPE-WRITER COMPANY, OF NEW YORK, N. Y., A CORPORATION OF DELAWARE

TYPEWRITING-MACHINE.

1,333,685.

Specification of Letters Patent. Patented Mar. 16, 1920.

Application filed June 28, 1918. Serial No. 241,378.

To all whom it may concern:

Be it known that I, Jesse A. B. Smith, a citizen of the United States, residing in Stamford, in the county of Fairfield and State of Connecticut, have invented certain new and useful Improvements in Typewriting-Machines, of which the following is a specification.

This invention relates to typewriting machines of the class disclosed in the Wernery and Smith Patent No. 1,132,055, dated March 18, 1915, in which a fan-fold web is led over a supplemental carriage on the typewriting machine to feed around the platen; said supplemental carriage being provided with a contrivance which may be used to pull back the carbon sheets which are interleaved with the plies of the fan-fold web; this being accomplished after the platen has been displaced upwardly to permit the straightening out of the web, where by the carbons may be slipped back freely between the plies of the web. The invention, however, is applicable to machines of other types than those in which a displaceable platen is employed; and one of the principal features of the invention is in the nature of means for facilitating the delivery of webs from rolls, particularly where the webs are not in fan-fold form.

Where several separate webs are employed, it is usual to supply them in roll form; the roll, because of its weight, being usually mounted upon a desk or some stationary part, and a long bight of web usually extending up from the spool to the typewriting machine to accommodate by its edgewise movement the to and fro traveling movements of the carriage. Owing to the great weight of the paper rolls, it has been found difficult to secure accurate line-feeding of the webs around the platen, because the line-spacing mechanism moves the platen freely, and it is found that the feed rolls which hold the webs against the platen do not have enough grip to pull the webs freely off from the paper rolls, but tend to remain stationary owing to their weight and inertia, so that the platen is apt to rotate while the paper rolls remain stationary or move slightly.

According to the present invention, improved means are provided for pulling the sheets off from the rolls in advance of the line-feeding movements of the platen, so

that the platen does not have to rotate said paper rolls, and hence the webs may feed accurately around the platen at line-spacing operations.

In my co-pending application, Serial Number 145,054, filed April 28, 1917, (now Patent No. 1,290,387, dated January 7, 1919), in which are embodied claims broad enough to cover the present improvements, there is disclosed one means of unwinding paper from the rolls in advance of the platen requirements; but this invention is limited to a specific improvement, which is simple in its construction and operation and readily applicable to existing machines.

The method of unwinding paper from the roll or rolls disclosed in the present application involves the use of the carbon shifter for an additional purpose, and at a time when it is not used for carbon-shifting purposes. In said Wernery and Smith patent, after the webs have been straightened out, the operative grasps the handle which belongs to the carbon shifter and pushes said handle rearwardly, together with the shifter, thus carrying the carbons back so that they face fresh portions of the webs. The same thing is done in the present case, but there is also thereafter a novel additional operation, which is that after said carbons have been pulled back in this manner, the operative closes a clamp upon the paper webs at a point in the rear of the carbons and while said clamp is closed, pulls forward the carbon shifter; this movement of the carbon shifter being idle so far as the carbons are concerned, but having the effect of pulling a fresh supply of paper off from all the rolls. The length of paper pulled off may be determined by the length of stroke of the carbon shifter, which may be greater than the extent of a form which is printed repeatedly along the webs. The operative then shifts the carbon carriage idly back to its rearmost position, thus restoring to normal condition the plies of web and interleaved carbon which extend between the carbon shifter and the platen; and also permitting the freshly unwound paper to fall back of the typewriter, where it may lie on the floor or depend in loops from the rolls. During the succeeding line feeding movements of the platen, the paper will feed around the platen without disturbing the rolls, and hence the difficulty of faulty line-

feeding of the webs around the platen is avoided. This extra operation is readily learned by the operative, and the mechanism involved is very simple and the device is efficient.

Other features and advantages will hereinafter appear.

In the accompanying drawings,

Figure 1 is a perspective view of a typewriting machine of the fan-fold type, showing my invention applied thereto, and the parts in position prior to a bight-forming operation.

Fig. 2 is a diagrammatic side view of the machine, showing the position of the parts when the webs are drawn from off the rolls to form a bight.

Fig. 3 is a view similar to Fig. 2, showing the parts in their normal position after a bight-forming operation.

The webs 10 are supplied to the machine from rolls 11, which are mounted in bearings in any suitable manner upon the bottom rear portion of a desk or other convenient place, and from said rolls the webs are carried up to a guide 12 provided upon the rear of the carriage portion 18 of the typewriting machine. From this guide 12 the webs are led forwardly to another guide 14 over which they pass downwardly and around the under side of the platen 15 and up in front thereof; the platen being rotated by the usual line-spacing mechanism including a lever 16, Fig. 1, and ratchet 17

and other parts (not shown). The carbons 18, which interleave the webs 10, are carried upon blades 19, Fig. 1, each of which at its end is mounted upon a carrier or shifter 20 which runs upon rails 21 extending rearwardly from the platen, said rails carried by a carriage 22, which is connected to travel with the typewriter carriage 18 and which runs upon a rail 23, Fig. 1, which is parallel with the typewriter carriage rails 24.

After the writing of a form, the platen 15 is swung up, as in said Werner and Smith patent, to permit the webs 10 to be straightened out, and then a handle 25, provided upon the carbon carrier 20, is grasped and the carbon carrier is pressed rearwardly, thus retracting the carbon sheets 18 to occupy positions opposite fresh portions of the webs 10; so that subsequently, after the platen has been returned to normal position, the line-space rotative movements of the platen will pull forward the carbons and the carbon carrier, together with the webs, line by line. Before the typing of the fresh form begins, or before the platen is returned to printing position, the operative, by means of said handle 25, pulls the carbon carrier 20 forward idly, first, however, operating a finger-piece 26 to close grippers or clamps 27 upon the webs in rear of the carbons, so that the forward movement of

said carbon carrier will exert a pull upon the webs at the rear of the typewriting machine and pull them off from the rolls 11, Fig. 2, to an extent which may be determined by the length of stroke of the carbon 70 carrier. This finger-piece 26, which controls the grippers 27, may be opposed to a finger-piece 28 which moves the carbon carrier, so that the operative needs only to grasp the finger-pieces 26, 28, between 75 thumb and finger, thereby closing the grippers 27 as well as pulling forward the carbon carrier, suitable connections extending from said movable finger-piece 26 to said grippers 27. During this idle forward 80 movement of the carbon carrier, the portions of the webs 10 between the same and the platen may bulge up idly, as at 29, Fig. 2; and then the operative may press back the carbon carrier 20 to restore these 85 intervening portions 29 of the webs with their carbons to normal condition, as at Fig. 3, and at the same time permit the freshly unwound portions 30 of the webs to drop idly; as illustrated at Fig. 3. Then, upon 90 operating the line-space lever 16, the platen 15 and its feed rolls 31 will pull forward the webs 10 without liability of faulty action, since the paper rolls 11 remain stationary until the typing of the next form is 95 completed; whereupon the cycle of operations may be repeated.

The connections between the finger-piece 26 and the clamps or grippers 27, to operate the latter, include a link 32 extending 100 rearwardly from said finger-piece and connected to the upper end of an upstanding arm 33 fast on a rock shaft 34 journaled in brackets 35 on the carbon-shifter 20. At each end of said rock shaft 34, Fig. 1, is fast 105 a clamp 27, placed so as to engage the webs 10 on their margins outside of the carbons 18 and held out of engagement therewith by a spring 36 coiled around one end of said rock shaft. To arrest the clamps 27 and 110 connected parts when moved out of engagement with said webs by said spring 36, there is provided on the carbon-shifter-handle 25 a pin 37 against which the finger-piece 26 abuts. To grip the webs 10 in a bight-forming operation, the finger-piece 26 and connected parts are moved against the tension of said spring 36, so that the forward ends of said clamps 27 press the webs 10 115 against an elevation 38 formed on the carbon-shifter 20.

Variations may be resorted to within the scope of the invention, and portions of the improvements may be used without others.

Having thus described my invention, I 125 claim:

1. In a typewriting machine, the combination with a traveling carriage, of a revolvable platen, means for feeding superposed webs to and around said platen, a clamp for 130

- positively holding said superposed webs together when advancing said webs toward said platen, and means for closing said clamp to permit it to be advanced with said webs toward said platen when the platen is at rest.
2. In a typewriting machine, the combination with a traveling carriage, of a revolute platen, line-spacing mechanism for feeding webs to and around said platen, and means other than said line-spacing mechanism for clamping unused portions of said webs together and for moving the same toward the platen when the platen is at rest.
- 15 3. In a typewriting machine, the combination with a traveling carriage, of a revolute platen, line-spacing mechanism for feeding webs to and around said platen, and means other than said line-spacing mechanism for moving said webs forwardly when the platen is at rest, said means holding said webs against displacement during said forward movement.
- 25 4. In a typewriting machine, the combination with a traveling carriage, of a revolute platen, a carbon shifter movable on said carriage for holding a carbon sheet, a clamp on said shifter for positively holding superposed webs together to move them toward the platen when said platen is at rest, a handle extending from said carbon shifter to enable the operative to push the shifter forwardly, and a finger-piece on said handle for operating said clamp to hold the webs.
- 35 5. In a typewriting machine, the combination with a traveling carriage, of a revolute platen thereon, means for feeding superposed webs to and around said platen, rails forming part of said carriage, a carbon-sheet shifter running on said rails, clamps on each side of said shifter for clamping the margins of said webs together, a spring normally tending to open said clamps, and a finger-piece for closing said clamps.
- 45 6. In a typewriting machine, the combination with a traveling carriage, of a revolute platen thereon, means for feeding superposed webs to and around said platen, rails forming part of said carriage, a carbon-sheet shifter running on said rails, clamps on each side of said shifter for clamping the margins of said webs together, a spring normally tending to open said clamps, a rock-shaft on which said clamps and spring are mounted, and a finger-piece on said shifter operatively connected with said rock-shaft for closing said clamps.
- 55 7. In a typewriting machine, the combination with a traveling carriage, of a revolute platen thereon, means for feeding superposed webs to and around said platen, rails forming part of said carriage, a carbon-sheet shifter running on said rails, clamps on each side of said shifter for clamping the margins of said webs together, and means for
- causing said clamps to constantly tend to release said webs.
8. In a typewriting machine, the combination with a traveling carriage, of a revolute platen thereon, a reciprocable carbon-shifter on said carriage, a roll of web, the leading portion of which is around said platen, a clamp for gripping said web, and a finger-piece for closing said clamp when said carbon-shifter is moved forwardly from said roll for forming a bight of web, so that the rotation of the platen will draw on the bight.
- 70 9. In a typewriting machine, the combination with a traveling carriage, of a revolute platen thereon, a reciprocable carbon-shifter on said carriage, a roll of web, the leading portion of which is around said platen, a clamp for gripping said web, a finger-piece for closing said clamp when said carbon-shifter is moved forwardly from said roll for forming a bight of web, so that the rotation of the platen will draw on the bight, and means for automatically releasing said clamp when said bight has been formed.
- 75 10. In a typewriting machine, the combination with a traveling carriage, of a revolute platen, means for feeding webs and interleaved carbons to and around said platen, means for displacing said platen to permit the straightening of the webs and the retraction of the carbons, and means mounted directly on said carbon-retracting means for drawing said webs from a source of supply 80 and advancing them toward said platen.
- 85 11. In a typewriting machine, the combination with a traveling carriage, of a revolute platen, means for feeding webs and interleaved carbons to and around said platen, means for displacing said platen to permit the straightening of the webs and the retraction of the carbons, and means traveling 85 with said carbon-retracting means for drawing said webs from a source of supply 90 and advancing them toward said platen.
- 95 12. In a typewriting machine, the combination with a traveling carriage, of a revolute platen mounted thereon, means for feeding webs and interleaved carbons to and around said platen, means for displacing the platen to permit the straightening of the webs and retraction of the carbons, and means traveling with said carriage for drawing 100 said webs from a source of supply and advancing them toward said platen.
- 105 13. In a typewriting machine, the combination with a traveling carriage, of a revolute platen thereon, rolls of webs, means for feeding said webs in superposed position with interleaved carbons to and around the platen, means on said carriage for retracting said carbons when the webs are straightened out, and means mounted on 115 said carriage and traveling therewith for 120 advancing them toward said platen.
- 125 14. In a typewriting machine, the combination with a traveling carriage, of a revolute platen thereon, rolls of webs, means for feeding said webs in superposed position with interleaved carbons to and around the platen, means on said carriage for retracting said carbons when the webs are straightened out, and means mounted on 130 said carriage and traveling therewith for 135 advancing them toward said platen.

- forming a bight of webs which may vibrate laterally to accommodate the traveling movements of said carriage, said bight-forming means being actively connected 5 with said carbon-retracting means.
14. In a typewriting machine, the combination with a traveling carriage, of a revoluble platen thereon, rolls of webs, means for feeding said webs in superposed 10 position with interleaved carbons to and around the platen, means on said carriage for retracting said carbons when the webs are straightened out, and means mounted on said carriage and traveling therewith for 15 forming a bight of webs which may vibrate laterally to accommodate the traveling movements of said carriage, said bight-forming means being operable after a carbon-retracting operation.
16. In a typewriting machine, the combination with a traveling carriage, of a revoluble platen thereon, substantially stationary rolls of webs, a line-spacing mechanism for feeding said webs in superposed 20 position with interleaved carbons to and around said platen, a shifter on said carriage for retracting said carbons when the webs are straightened out, and means, other than said line-spacing mechanism, operable 25 after a carbon-retracting operation for drawing said webs off from the rolls and advancing them toward said platen.
17. In a typewriting machine, the combination with a traveling carriage, of a revoluble platen thereon, rolls of webs, means for feeding said webs in superposed position with interleaved carbons to and around the platen, means on said carriage for retracting said carbons when the webs 30 are straightened out; a clamp mounted on said carbon-retracting means, operable after a carbon-retracting operation, for gripping the webs and drawing them off from the rolls, and a spring for releasing said clamp 35 to permit the clamp to be returned to position for subsequently gripping a fresh portion of said webs.
18. In a typewriting machine, the combination with a traveling carriage, of a revoluble platen thereon, substantially stationary rolls of webs having successive forms printed thereon, line-feeding mechanism for feeding said webs in superposed 40 position from the rolls with interleaved carbons to and around the platen, a reciprocable carbon-shifter on said carriage for retracting said carbons when the webs are straightened out, and means on said shifter and traveling therewith for forming a bight of webs which may vibrate laterally to accommodate the traveling movements of the carriage, said bight-forming means operable after the carbon-retracting operation, said shifter being capable of having a 45 greater forward stroke imparted thereto during a bight-forming operation than is required to accommodate the line-feeding movement to type a set of forms.
19. In a typewriting machine, the combination with a traveling carriage, of a revoluble platen thereon, rolls of webs, means for feeding said webs in superposed position with interleaved carbons to and around the platen, means on said carriage for retracting said carbons when the webs 50 are straightened out, and means mounted on said carbon-retracting means and traveling therewith for forming a bight of webs which may vibrate laterally to accommodate the traveling movements of said carriage, said bight-forming means being operable at another than a carbon-retracting operation.
20. In a typewriting machine, the combination with a traveling carriage, of a revoluble platen thereon, substantially stationary rolls of webs, line-spacing mechanism for feeding said webs in superposed position with interleaved carbons to and around the platen, a carbon-shifter traveling on and with said carriage for retracting said carbons when the webs are straightened out, said shifter having a handle; and means mounted on said carbon-shifter and traveling therewith for forming a bight of webs which may vibrate laterally to accommodate the traveling movements of said carriage, said bight-forming means including a pair 55 of clamps for pressing the webs to said shifter, a rock shaft on which said clamps are fast, an arm fast on said rock shaft, a link extending between said arm, a finger-piece operatively mounted on said shifter handle, a stop on said handle for said finger-piece, and a spring normally holding said clamps open.
21. In a typewriting machine, the combination with a traveling carriage, of a revoluble platen, means for feeding webs and interleaved carbons to and around said platen, means for displacing said platen to permit the straightening of the webs and the retraction of the carbons, and means mounted directly on said carbon-retracting means for drawing said webs from a source of supply and advancing them toward said platen, said web-drawing means serving to return said webs toward the source of supply.
22. In a typewriting machine, the combination with a revoluble platen, of rolls of webs, means for feeding said webs in superposed position with interleaved carbons to and around said platen, a reciprocable carbon-shifter for retracting said carbons when the webs are straightened out, and means mounted on said carbon-shifter for drawing said webs off from the rolls to form a bight of webs between said shifter and platen when said shifter is moved forwardly, and to form a bight between said rolls and shifter when the latter is moved rearwardly.

22. In a typewriting machine, the combination with a traveling carriage, of a revolute platen on said carriage, a reciprocable carbon-shifter on said carriage, a roll of web, the leading portion of which is around said platen, a clamp for gripping said web, and a finger-piece for closing said clamp when said carbon-shifter is moved forwardly and rearwardly for forming a bight of web, 10 so that the rotation of the platen will draw on the bight.

23. In a typewriting machine, the combination with a traveling carriage, of a revolute platen on said carriage, a reciprocable carbon-shifter on said carriage, a roll of web, the leading portion of which is around said platen, a clamp for gripping said web, and a finger-piece for closing said clamp when said carbon-shifter is moved forwardly and rearwardly after a carbon-retracting operation for forming a bight of web, so that the rotation of the platen will draw on the bight.

24. In a typewriting machine, the combination with a traveling carriage, of a revolu-

lute platen, means for feeding webs and interleaved carbons to and around said platen, means for displacing said platen to permit the straightening of the webs and the retraction of the carbons, a reciprocable carbon-shifter for retracting said carbons, and means mounted on said carbon-shifter for drawing said webs from a source of supply to form a bight of webs, so that the rotation of the platen will draw on the bight, said 35 bight being formed at alternate reciprocations of said shifter.

25. In a typewriting machine, the combination with a traveling carriage, of a revolute platen, rolls of webs, means for feeding said webs in superposed position with interleaved carbons to and around the platen, and a single device for retracting said carbons and for drawing said webs off from the rolls to form a bight of webs which 45 may vibrate laterally to accommodate the traveling movements of said carriage.

J. A. B. SMITH.
